Primary Examiner — Cynthia M Chin(74) *Attorney, Agent, or Firm* — Dunlap Bennett & Ludwig PLLC(57) **CLAIM**

The ornamental design for a valve handle, as shown and described.

DESCRIPTION

FIG. 1 is a perspective view of a valve handle, showing my new design;

FIG. 2 is a front elevation view thereof;

FIG. 3 is a top plan view thereof;

FIG. 4 is a rear elevation view thereof;

FIG. 5 is a bottom plan view thereof; and,

FIG. 6 is a right side elevation view thereof, the left side elevation view is a mirror image thereof.

The dash-dot boundary lines represent the bounds of the claim and all other broken lines represent environmental subject matter. None of the broken lines form a part of the claimed design.

1 Claim, 4 Drawing Sheets(56)
